(57) **CLAIM**

The ornamental design for a silencer tube with reduced profile, as shown and described.

DESCRIPTION

FIG. 1 is a side perspective view of a silencer tube with reduced profile showing my new design;

FIG. 2 is a side elevation view thereof;

FIG. 3 is a cross-sectional view taken along section line 3—3 of FIG. 2; and,

FIG. 4 is a top view thereof.
